UNITED STATES PATENT OFFICE.

HARRY E. AINE, OF RICHMOND, CALIFORNIA.

MACHINE FOR DOUBLE-WINDING PIPES OR PIPE-COVERINGS.

1,146,912.

Specification of Letters Patent. Patented July 20, 1915.

Application filed June 14, 1913. Serial No. 773,712.

To all whom it may concern:

Be it known that I, HARRY E. AINE, a citizen of the United States, residing at Richmond, in the county of Contra Costa and 5 State of California, have invented certain new and useful Improvements in Machines for Double-Winding Pipes or Pipe-Coverings, of which the following is a specification.

10 The present invention relates to improvements in continuous wire wound wooden stave pipe or pipe covering constructed in the ditch or place where used and the apparatus for winding the same, and the invention 15 has for its principal objects, to provide an apparatus for winding a pipe or pipe covering with a plurality of wrappings or coils of wire, whereby on the breaking of one strand, the others will prevent the staves of 20 the pipe or covering from becoming displaced and will retain the same in position until the broken strand can be mended or a portion of the pipe rewound; to provide an apparatus which will simultaneously wind a 25 pipe or covering of the above type with a plurality of coils of wire in one operation, and each coil arranged in parallel spaced relation to the other; and to provide an apparatus which is capable of assembly over a 30 constructed pipe without cutting the same.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the appended claims may be 40 resorted to without departing from the spirit or sacrificing any of the advantages of the invention.

To more fully comprehend the invention, reference should be had to the accompanying drawings wherein is disclosed one form of my invention, and in which—

Figure 1 is a view in elevation of my invention mounted on a pipe, disclosing the winding apparatus, the two separate strands 50 of wire wound thereby on the pipe, the double wire feed and tension mechanism, and the reel for holding the separate strands of wire. Fig. 2 is a vertical sectional view taken on line 2—2 of Fig. 1, disclosing more 55 fully the pipe encircling shells, the annulus,

the driving means therefor, and the position of the tension and feed mechanism for the respective strands of wire. Fig. 3 is a section of the toothed annulus at the junction of the sections thereof.

60

Referring more particularly to the drawings, wherein like reference numerals designate corresponding parts throughout the several views, the numeral 1 indicates a suitable annulus constructed of two semi-circular segments, the ends of which overlap and are joined by the bolts 2. An annular groove 3 is provided on each side of the annulus and in the same operate the rollers 4 carried on the inner surfaces of the cheek plates 5, which are connected at their upper edges to one end of a laterally extending arm 6, which is supported at one side of the trench on a suitable movable dolly 7. The annulus is provided on its peripheral edge 75 with teeth 8, which intermesh with a pinion 9 mounted between the cheek plates 5, and which is rotated by a suitable motor 10, thus transmitting power to the annulus.

80 Detachably mounted within the annulus is a pipe encircling shell, comprising the semi-circular members 11 and 12, provided at their edges with flanged plates 13 through which extend the bolts 14 which retain the shell around the pipe.

85

Pivots mounted as at 15 on the interior surface of the respective shells are the semi-circular equi-distant pitch giving bars 16, preferably V-shaped in cross section and pivotally connected at their opposite ends to 90 the respective sliding plates 17 and 18, carried by the sections, the plates 18 being adjusted through the medium of the bolts 19 which connect with flanges 20 carried by the respective members 11 and 12. The pitch 95 giving bars project inwardly and act as threads when embracing the exterior surface of the staves, and their slight biting action into the exterior surface of the staves causes the entire wire winding mechanism to advance regularly, and progressively longitudinally of the pipe and tightly wind the two strands therearound in parallel spaced relation to each other. By adjusting the inclination of the pitch giving bars, the inclination 105 of the spirals may be varied.

100 Mounted on the exterior surface of the respective semi-cylindrical shells 11 and 12, and located at diametrically opposite points from each other, are the wire feed and ten- 110

sion devices A and B, which are rotatable with the shell and through which the respective wires pass when being wound onto the pipe. The structures each consist of a plurality of rollers 21 mounted between plates 22 secured to the respective shells and over said rollers passes the wire which is being wound onto the pipe, the tension exerted on the wire being regulated by the adjustable 5 rollers 23, carried by the plates 22, and positioned between the rollers 21, and between which and the rollers 21 passes the wire.

10 It will be apparent that by positioning the feeding devices for the respective wires at 15 opposite points on the shells, that the wires will be wound around the pipe in alternate spirals.

15 The device being mounted on the assembled staves and power being supplied from 20 the motor 10 to rotate the annulus and shell in the direction of the arrow—Fig. 1, the device operates in the following manner in applying the double spiral windings of wire to the pipe. The wires 24 and 25, which are 25 both unwound from the reel 26 are passed respectively downwardly around and under the shell, through the winding and tension device A, through an opening in the shell where it is suitably attached to the staves; 30 and downwardly, under, upwardly and over the shell, through the winding and tension mechanism B, through an opening 28' in the shell and onto the pipe, where it is attached to staves in any suitable manner, and 35 as the shell is rotated about the pipe, the wires 24 and 25 will be wound therearound in alternately disposed, equidistant spaced, continuous spirals, and the engagement of the pitch giving bars 16 slightly biting into 40 the staves and contacting at their rear side faces with the forward edges of the tightly wound spirals, will cause the entire winding mechanism to advance regularly and progressively longitudinally of the staves.

45 It will be apparent that the rotation of the shell about the pipe will automatically advance the dolly along its supporting track and the same will prevent the movement of the motor and pinion in the direction of 50 rotation of the annulus.

55 From the above description it will be observed that I have provided a pipe winding or pipe cover winding machine, which is capable at one operation of winding a plurality of separate and distinct wires in alternately disposed parallel spaced coils about the pipe or covering; is capable of being positioned over a constructed pipe without cutting the same; and is provided

with means for varying the inclination of 60 the spirals.

It will be apparent that by securing the spiral coils to the pipe or covering at spaced intervals as at C, that a double winding is provided for the pipe or covering and that 65 should one wire break, the other wire will retain the staves together until the broken strand can be mended.

Having thus described my invention what I claim as new and desire to protect by Letters Patent is:—

1. A wire winding apparatus including a rotatable annulus, a cylindrical structure encircling shell mounted within said annulus and rotatable therewith, a plurality of tension devices mounted upon the shell, each of said tension devices being adapted to receive a separate strand of wire to be fed through the shell, whereby to apply the wire to the structure in independent coils, the convolutions of which are spaced longitudinally of the structure, and means for rotating the annulus. 75

2. A wire winding apparatus including a rotatable annulus, a cylindrical structure encircling shell mounted within said annulus and rotatable therewith, a plurality of spaced tension devices mounted in the same plane upon the shell, each of said tension devices provided with a series of rollers and 80 adapted to receive a separate strand of wire to be fed through spaced openings in the shell, thereby applying the wire to the structure in independent coils, two series of pitch bars arranged within the shell, means for independently adjusting the inclination of each series of bars, whereby the convolutions of the wire are spirally spaced longitudinally of the structure, and means for 85 rotating the annulus. 90

3. A wire applying apparatus including a rotatable annulus, a cylindrical structure encircling shell mounted within the annulus and rotatable therewith, means for feeding two separate strands of wire through the shell, two series of pitch bars arranged within the shell whereby the convolutions of the wire are spaced longitudinally of the structure, and means for rotating the annulus. 105

110 In testimony whereof I have signed my name to this specification in the presence of two subscribing witnesses.

HARRY E. AINE.
